UNITED STATES PATENT OFFICE.

JAMES McROBERTS, OF WHAT CHEER, IOWA, ASSIGNOR OF ONE-THIRD TO A. W. McDONOUGH, OF WHAT CHEER, IOWA.

WIRE CLOTHES-PIN.

1,255,118.

Specification of Letters Patent. Patented Jan. 29, 1918.

Application filed October 17, 1916. Serial No. 126,167.

To all whom it may concern:

Be it known that I, JAMES McROBERTS, a citizen of the United States, and resident of What Cheer, in the county of Keokuk and 5 State of Iowa, have invented certain new and useful Improvements in Wire Clothes-Pins, of which the following is a specification.

The present invention relates to buckles, 10 buttons and clasps and has particular reference to new and useful improvements in wire clothes pins.

An object of my invention is to provide a clothes pin of the class referred to having a 15 novel arrangement of parts whereby the same may be formed from a single strand of wire.

Another object of my invention is to provide a pin of the class described which will not in any way mutilate the garment or the 20 like held thereby on a clothes line.

A further object of my invention is to provide a clothes pin of the class described which is cheap to manufacture, strong and durable, quickly and easily applied for use 25 and effective in operation.

Other objects and advantages to be derived from the use of my improved clothes pin will appear from the following detailed description and the claim, taken with an 30 inspection of the accompanying drawing, in which:

Figure 1 is a perspective view of a clothes pin embodying the improvements of my invention, the same being shown in use;

35 Fig. 2 is a side elevational view of a pin, a portion thereof being in section the same being shown in use; and

Fig. 3 is a front view of the same.

Referring more particularly to the drawing, wherein similar characters of reference 40 designate like and corresponding parts throughout the various views, S designates a strand of wire from which my improved clothes pin is formed, said strand being 45 coiled as at 10 approximately intermediate its ends to form a spring. One portion of the strand of wire S forms one arm of the pin and is designated 11, the free end of the arm 11 being bent upon itself as at 12 forming 50 a parallel portion 13 which co-operates with the arm 11 to form a gripping jaw. The free end of the portion 13 is bent inwardly as is best shown in Fig. 3 to prevent the same from catching in the garment to be

held and to eliminate sharp corners or projecting parts as much as possible. 55

The other arm of the pin is designated 14 and is bent approximately at right-angles as indicated at 15 to form a laterally extending portion 16 which projects between the arm 60 11 and the parallel portion 13 bent therefrom. A hook 17 is formed in the portion 16, said hook terminating in a V-shaped gripping element 18. The gripping element 65 is provided with a laterally off-set portion 19 to provide a finger engaging member. A clothes line has been shown and designated 20, a garment 21 being draped thereover.

In use my improved clothes pin is applied as shown in Fig. 1. The V-shaped gripping 70 portion 18 is adapted to engage the garment between the arm 11 and the portion 13 as best shown in Fig. 2. To apply the pin the arms 11 and 14 are merely compressed, the garment previously being draped over the 75 clothes line. Of course, the garment when gripped is distorted slightly but this distortion may be easily removed when the garment is pressed after drying. Compression of the arms 11 and 14 causes the gripping 80 member 18 to move to a point remote from the arm 11 and the portion 13 thereby permitting application of the pin to the garment. The portion 17 of the arm 14 serves to engage the garment adjacent the point 85 in which the latter is draped over the clothes line and the V-shaped portion 18 engages beneath the clothes line so that the garment is both prevented from moving longitudinally upon the clothes line and from being 90 dislodged laterally therefrom.

From the above description taken in connection with the accompanying drawing, it is thought that a clear and comprehensive understanding of the construction, operation 95 and advantages of my invention may be had, and while I have shown and described the device as embodying a specific structure, I desired that it be understood that such changes may be made in said structure as do 100 not depart from the spirit and scope of the invention as claimed.

Having thus fully described my invention, what I claim as new and desire to secure by Letters Patent, is:—

A clothes pin of the class described formed of a single strand of wire coiled intermediate its ends to form a straight arm and a spring 105

arm, said spring arm diverging from the straight arm, a loop formed on the lower end of the straight arm in a plane at right angles to the plane in which the arms are disposed, a laterally and inwardly extending portion on the spring arm projecting through the upper section of the said loop, the end of said portion being bent back upon itself and adapted to engage a clothes

line to hold the same securely against the 10 adjacent side of the loop, and the extremity of the line engaging portion extending outwardly and downwardly through the loop to a point below the bottom thereof to form a garment gripping portion. 15

In testimony whereof, I affix my signature hereto.

JAMES McROBERTS.
